ELECTRICAL APPARATUS

Charles C. Whittaker, Pittsburgh, Pa., assignor to
Westinghouse Electric & Manufacturing Com-
pany, East Pittsburgh, Pa., a corporation of
Pennsylvania

Application November 29, 1939, Serial No. 306,660

10 Claims. (Cl. 200—113)

This invention relates to electrical apparatus and particularly to switching apparatus of the vibratory type such as is used in voltage regulators.

In vibrating regulators, it is found that the contact members develop a high resistance contact surface. Upon examination, it is found that this high resistance surface is developed by a deposit of material from one contact member on to the other to such an extent that pinnacles are formed on the contact surface. It is thought that these pinnacles are formed by reason that the contact members always mate on a corresponding point with the result that a pinnacle is formed on one contact while a valley is formed on the other contact member. With such pinnacles formed on the contact surface of the contact members, if the contact members are moved, it is possible that two of the pinnacles will mate giving a point of extremely high resistance on the contact surface, with the result that the contact members have to have their contact surfaces redressed quite frequently.

An object of this invention is to provide for increasing the life of the contact members of a switching apparatus.

Another object of this invention is to provide a switching apparatus having a contact member so mounted as to prevent movement of its contact surface out of a fixed plane, while permitting movement in the fixed plane relative to a contact member which is disposed to be actuated into and out of engagement therewith.

A further object of this invention is to provide a switching apparatus having a contact member mounted in a fixed plane and a contact member disposed to be actuated into and out of engagement therewith, the mounted contact being actuated by a bimetal element to move in the fixed plane to different positions relative to the other contact member.

Other objects of this invention will become apparent from the following description, when taken in conjunction with the accompanying drawing, in which

Figure 1 is a view in side elevation of a regulator embodying the teachings of this invention;

Fig. 2 is an end view of the regulator illustrated in Fig. 1;

Fig. 3 is a bottom plan view of the left-hand contact of the regulator shown in Fig. 1; and

Fig. 4 is a circuit diagram illustrating one manner of connection of the regulator illustrated in Fig. 1 in a circuit to control the voltage of a generator.

Referring to the drawing, a supporting panel 10 is provided upon which is mounted a core structure 12 comprising a winding leg 14 extending between two lateral core legs 16 and 18 and secured in position as by the screws 20. The core structure 12 is securely mounted on the panel 10 by means of the screws 22 shown in Fig. 2. In addition to the core legs 16 and 18, the core also includes a portion 24 attached to the leg 16 by means of the screw 26 and which terminates a distance spaced from the adjacent end of the leg 18 to provide a space therebetween for accommodating an armature 28 of magnetic material mounted on a lever 30 of non-magnetic material. A movable contact member 32 comprising a two-faced contact member, as illustrated, is mounted upon the upper end of the lever 30 and is adapted to engage either contact member 34 or 36 which are mounted on the panel 10, as will be explained hereinafter.

In order to provide a pivot for the lever 30, a block 38 having a lower corner beveled, as at 40, is attached to the side of the lever 30 in position opposite a similar bevel 42 on the end of the leg 16 of the core structure and is attached to the core structure 12 through a plurality of flat springs 44 and 46 disposed at right angles to each other and attached to the block 38 by screws 48 and 50, respectively, and to the leg 16 by screws 26 and 52, respectively. These flat springs, usually two springs of each of 44 and 46 spaced apart, form a pivot or hinge for the lever 30 about the axis along the intersection of the plane of the springs, as shown, about which the movable structure can pivot.

As illustrated, the winding leg 14 carries an operating winding 54 disposed between the legs 16 and 18 for energizing the magnetic circuit. In order to cause the center of gravity of the movable element to coincide with the pivotal axis formed by the springs 44 and 46, a counterweight 56 is provided at the lower end of the lever 30 and secured thereto as by means of screws 58.

In order to adjust the tension on the lever 30, an adjustable helical spring 60 is provided having one end attached to a bracket 62 mounted on the panel 10 and the other end attached to the lever 30 through an adjustable securing device 64 having set screws 66 and 68 for laterally adjusting the tension of the spring 60.

As illustrated, the movable contact member 32 is positioned to engage either contact member 34 or 36 which are provided having contact surfaces in fixed parallel planes disposed in definite spaced relation to each other. These contact members

are similarly mounted on the panel 10. In order to provide for movement of the contact member 34 in a fixed plane parallel to the plane of the contact surface of contact 32 while remaining stationary with respect to the fixed distance between the stationary contact members 34 and 36, the contact members 34 and 36 are each mounted on the panel 10 by means of a bimetal support 70.

Referring particularly to Figs. 2 and 3, the support 70 for contact member 34 comprises two bimetal members 72 and 74, the bimetal member 72 being of substantially U-shape having one leg longer than the other while the bimetal member 74 is of substantially L-shape. These bimetal members are mounted on the panel 10 with one leg of each of the bimetal elements overlapping and are secured to the panel as by means of the screws 76. As illustrated, the bimetal member 72 carries a substantially U-shaped bracket member 78 for supporting the contact member 34. One of the legs 79 of the bracket member 78 is so secured to the longer leg of the bimetal member 72 by means of the screws 80, as to position the center portion of the bracket 78 for forming the contact carrying face of the support 70. In this position the contact carrying face of the bracket 78 is disposed in a plane which cuts the bimetal members at substantially right angles along their longest dimensions. Thus, the contact carrying face of the bracket 78 is in a plane parallel to the plane through which the bimetal elements expand when heated, as referred to hereinafter. The direction of the expansion of the bimetal members will be such as to tend to straighten the bimetal members or to bend them depending upon which side of the individual bimetal member is the high expansion component of the member. For illustrating this invention, the bimetal members are positioned with the high expansion component adjacent the contact member 34 so that when heated the bimetal members will tend to straighten and thereby move farther apart.

In the embodiment illustrated in Figs. 2 and 3, when the U-shaped bracket member 78 is mounted in assembled relation with the bimetal member 72, the other leg 82 of the bracket 78 extends away from the contact carrying face and has its outer edge in abutting engagement with a stop 84. The stop 84 is of substantially L-shape and is so secured to the base or overlapped portion of the bimetal elements 72 and 74 and to the panel 10 by means of the screws 76 as to have one of its legs project outwardly from the base portion to engage the leg 82 and prevent movement of the U-shaped bracket 78 out of the fixed plane, as will be explained more fully hereinafter.

The contact member 34 is carried by the U-shaped bracket 78 being secured thereto by means of the screw 86. As more clearly illustrated in Fig. 2, the legs of the bimetal members 72 and 74 opposite their overlapped and secured ends are interlocked, the bimetal member 74 having a recess 88 cut into the outer edge thereof as illustrated in Fig. 3, while the bimetal member 72 terminates in a tongue 90 which fits into the recess 88 of its cooperating bimetal element. Thus with the bimetal members 72 and 74 mounted to form a substantially rectangular enclosure, it is apparent that when heated the bimetals will expand and straighten. Because of the tongue and groove relation between the bimetal members, the plane of movement of the members

with respect to each other is in a fixed plane, the line of movement of the members as they tend to straighten being in a plane which passes through the longest dimensions of the bimetal member and which is parallel to the desired fixed plane of the contact surface of contact member 34. This interlocked joint between the bimetal members 72 and 74 prevents torsional movement of the bimetal support for the contact member 34. It is, of course, to be understood that the bimetal support described with respect to the contact member 34 is duplicated for the contact member 36, the support for the contact member 36 comprising the elements of the support described except that they are mounted in the reverse order.

Referring to Fig. 4, a generator 92 is provided having an armature winding 94 connected to circuit conductors 96 and 98 and a field winding 100 that is connected between a junction point 102 on the conductor 96 through a resistor 104 to a junction point 106 on the conductor 98. The movable contact member 32 of the regulator is connected to a junction point 108 between the field winding 100 and resistor 104. The regulator contact member 34 is connected through the bimetal support 70 and conductor 110 to the junction point 102 on conductor 96, while the regulator contact member 36 is connected through the other bimetal support 70, conductor 112, to the junction point 106 on conductor 98. The regulator winding 54 is connected to be energized in accordance with the voltage between conductors 96 and 98, as illustrated.

The tension of the spring 60 is adjusted to accord with the voltage desired to be maintained between conductors 96 and 98. This spring normally biases the contact member 32 into engagement with the contact member 36 to shunt the resistor 104 from the circuit of the field winding 100. As the voltage of the generator armature 94 increases, the current through the generator field winding 100 and the regulator also increases until the energization of the winding 54 increases sufficiently that the pull on the armature 28 becomes sufficient to overcome the pull of the spring 60, thus moving the armature 28 in a counterclockwise direction about the pivot formed by the springs 44 and 46 against the pull of the spring 60 to separate the contact member 32 forming the contact member 36. This introduces the resistor 104 in circuit with the field winding 100 between conductors 96 and 98, decreasing the energization of the generator and causing the voltage thereof to decrease. The decrease in the energization of the winding 54 causes the pull on the armature 28 to decrease sufficiently that the force of the spring 60 moves the armature 28 in a clockwise direction and causes engagement of the contact member 32 with the contact member 36. The regulator is sufficiently sensitive that the repeated engagement of the contact member 32 with the contact member 36, and separation therefrom, takes place at such a rapid rate that the voltage between the conductors 96 and 98 does not vary appreciably from the desired value.

If the generator is operated at such a high speed that the residual magnetism is sufficient to cause the energization of the winding 54 to maintain the generator voltage above the desired value with the contact members 32 and 36 out of engagement, the pull on the armature 28 will continue until the counterclockwise movement thereof is sufficient to cause the contact member 32

to engage the contact member 34 and short circuit the field winding 100. The continued vibrations of the regulator will, under this condition, cause repeated engagement of the contact member 32 with, and separation from, the contact member 34 instead of with and from the contact member 36.

In all these operations described hereinbefore, each of the bimetal supports 70 for supporting the contact member 34 and the contact member 36 is in circuit with the contact member which it supports, so that when the movable contact member 32 engages either the contact member 34 or 36, current passes directly through the bimetal support 70 of the contact member engaged. As will readily be appreciated, the I^2R losses in the bimetal due to the passage of the current through the bimetal will so heat the bimetal members that when they expand they tend to straighten and move with respect to each other in the fixed plane parallel to the plane of the contact surface of contact member 34 or 36. The movement of the bimetal members 72 and 74 effects a movement of the contact member 34 or 36 so as to vary the position of the contact surface of the contact member in its initially fixed plane. Where the movable contact member 32 is engaging either one of the contact members 34 or 36, it is found that the heat conducted into the bimetal from the contact or changes in the ambient temperature is sufficient to effect a movement of the bimetal support and consequently of the contact member supported thereby. Thus as the contact member 32 is rapidly vibrating between the contact members 34 and 36 or into engagement with either of the contact members 34 and 36, it is evident that due to the characteristics of the bimetal support, the contact member initially mounted in a fixed plane with respect to the contact member 32 is constantly varying its position in the fixed plane to vary the point contacts between the contact member 32 and the contact member which it is actuated to engage.

Although the interlocked ends of the bimetal 72 and 74 prevent torsional movement of the bimetal members during the operation thereof and the bimetal are mounted on edge as illustrated in Figs. 2 and 3, so that movement perpendicular to the initially fixed plane is substantially impossible, it is evident from the provision of the stop 84 that means is provided whereby it is impossible to move the contact member 34 or the similarly mounted contact member 36 out of its initially fixed plane even under the contact pressures developed when the contact member 32 is actuated into engagement therewith, the stop 84 effectively preventing all movement except that in the fixed plane as initially determined. In practice, where contact members are mounted on the bimetal supports, it is found that approximately $\frac{3}{2}$ of an inch of motion is obtained in the fixed plane of the contact surface of contact members 34 and 36 for a change in temperature of 35° F. Such motion of the contact members in the fixed plane aids in keeping the contact surfaces flat and prevents formation of irregularities on the surfaces, thereby prolonging the life of the contact members.

Although this invention has been described with reference to a particular embodiment thereof, it is intended that all matters contained in the description given hereinbefore shall be interpreted as illustrating and not in a limiting sense.

I claim as my invention:

1. In a switching apparatus, the combination comprising, a first contact member, a second contact member disposed to be actuated into and out of engagement with the first contact member, the first contact member having a contact surface in a fixed plane, and means for supporting the first contact member to maintain its contact surface in the fixed plane, said means being responsive to predetermined thermal conditions to actuate the first contact member to vary the position of its contact surface in the fixed plane with respect to the second contact member.

10 2. In a switching apparatus, the combination comprising, a first contact member, a second contact member disposed to be actuated into and out of engagement with the first contact member, the first contact member having a contact surface in a fixed plane, and means for supporting the first contact member to maintain its contact surface in the fixed plane, said means actuating the first contact member under predetermined conditions to vary the position of its contact surface in the fixed plane with respect to the second contact member.

15 3. In a switching apparatus, the combination comprising, a first contact member, a second contact member disposed to be actuated into and out of engagement with the first contact member, 20 each of the contact members having contact surfaces disposed in parallel planes when the contact members are in engagement, the contact surface of the first contact member being in a fixed plane at all times, and a support including 25 a bimetal member for retaining the first contact member in the fixed plane, the bimetal member under predetermined conditions actuating the first contact member to different positions in the fixed plane relative to the second contact member.

40 4. In a switching apparatus, the combination comprising, a first contact member, a second contact member disposed to be actuated into and out of engagement with the first contact member, 45 the first contact member having a contact surface in a fixed plane, and a support including a plurality of bimetal members for carrying the first contact member, the bimetal members being interlocked to prevent torsional movement thereof and to insure movement of the contact member carried thereby in the fixed plane under predetermined conditions whereby the first contact member presents different contact points for different operations when the second contact member is actuated into engagement therewith.

50 5. In a switching apparatus, the combination comprising, a first contact member having a contact surface, a second contact member disposed to be actuated into and out of engagement with the first contact member, and means for supporting the first contact member to maintain its contact surface in a fixed plane, the supporting means including a bimetal member disposed for movement under predetermined conditions, means for securing the first contact member to the bimetal member whereby the first contact member moves in response to movement of the bimetal member, and means associated with the bimetal member for limiting movement of the first contact member to the fixed plane.

60 6. In a switching apparatus, the combination comprising, a first contact member having a contact surface in a fixed plane, a second contact member disposed to be actuated into and out 65 of engagement with the first contact member,

and means for supporting the first contact member to maintain its contact surface in a fixed plane while permitting movement of the first contact member to vary the position of its contact surface in the fixed plane with respect to the second contact member, the supporting means including a plurality of bimetal members disposed for movement in a fixed plane in response to predetermined conditions, means for securing the first contact member to one of the bimetal members whereby it moves in response to movement of the bimetal members, and a stop disposed to cooperate with the securing means to prevent movement of the first contact member from the fixed plane under contact pressure of the second contact member when it is actuated into engagement therewith.

7. In a switching apparatus, the combination comprising a first contact member having a contact surface in a fixed plane, a panel for carrying the first contact member, a second contact member disposed to be actuated into and out of engagement with the first contact member, and means for supporting the first contact member to maintain its contact surface in a fixed plane while permitting movement of the first contact member to vary the position of its contact surface in the fixed plane with respect to the second contact member, the supporting means including a plurality of bimetal members disposed for movement in response to predetermined conditions, one of the bimetal members being substantially U-shaped, the other of the bimetal members being substantially L-shaped, a leg of each of the bimetal members being overlapped and secured to the panel, the other legs of the bimetal members being interlocked whereby the members are positioned for movement in a plane parallel to the fixed plane, means for securing the first contact member to the U-shaped bimetal member to obtain a movement of the first contact member in response to movement of the bimetal member, a stop disposed to cooperate with the securing means to prevent movement of the first contact member from the fixed plane under contact pressure of the second contact member when it is actuated into engagement therewith.

8. In a switching apparatus of the vibratory type, the combination comprising, a plurality of contact members disposed in spaced relation having their contact surfaces in parallel fixed planes,

5 a contact member positioned between the spaced contact members and disposed to be actuated into or out of engagement with either of them, a panel for carrying the spaced contact members, and a support for mounting each of the spaced contact members on the panel, each of the supports comprising a bimetal member secured to the panel, means for mounting the contact member on the bimetal member, and means associated with the bimetal member to retain the contact surface of the contact member in its fixed plane, the bimetal member under predetermined conditions actuating the contact member carried thereby for effecting movement of the contact member in the fixed plane with respect to the contact member positioned between the spaced contact members.

9. In a switching apparatus, the combination comprising, a first contact member, a second contact member disposed to be actuated into and out of engagement with the first contact member, the first contact member having a contact surface in a fixed plane, means for supporting the first contact member to maintain its contact surface in the fixed plane, said means actuating the first contact member under predetermined conditions to vary the position of its contact surface in the fixed plane with respect to the second contact member, and a stop disposed to cooperate with said supporting means to prevent movement of the first contact member from the fixed plane under contact pressure of the second contact member when it is actuated into engagement therewith.

10. In a switching apparatus, the combination comprising, a first contact member, a second contact member disposed to be actuated into and out of engagement with the first contact member, the first contact member having a contact surface in a fixed plane, and a support including a bimetal member disposed for movement under predetermined conditions for carrying the first contact member, means associated with the bimetal member disposed to prevent torsional movement thereof and to insure movement of the contact member carried thereby in the fixed plane whereby the first contact member presents different contact points for different operations when the second contact member is actuated into engagement therewith.

CHARLES C. WHITTAKER.
